UNITED STATES PATENT OFFICE

147,099

DESIGN FOR A STAIRCASE

Frank J. Zavada, Pittsburgh, Pa., assignor to Carnegie-Illinois Steel Corporation, a corporation of New Jersey

Application March 3, 1945, Serial No. 118,255

Term of patent 14 years

(Cl. D13—7)

To all whom it may concern:

Be it known that I, Frank J. Zavada, a citizen of the United States and a resident of Pittsburgh, in the county of Allegheny and State of Pennsylvania, have invented a new, original, and ornamental Design for a Staircase, of which the following is a specification, reference being had to the accompanying drawing, forming part thereof.

Figure 1 is a perspective view of a staircase, showing my new design; and

Figure 2 is an enlarged fragmentary sectional view taken on line II—II of Figure 1.

I claim:

The ornamental design for a staircase, as shown.

FRANK J. ZAVADA.
